US00D999021S

(12) **United States Design Patent** (10) **Patent No.:** **US D999,021 S**
Li (45) **Date of Patent:** **** Sep. 19, 2023**

(54) **WATER BOTTLE**

(71) Applicant: **Ting Li**, Jiaxing (CN)

(72) Inventor: **Ting Li**, Jiaxing (CN)

(**) Term: **15 Years**

(21) Appl. No.: **29/889,235**

(22) Filed: **Apr. 10, 2023**

(51) LOC (14) Cl. **07-01**

(52) U.S. Cl.

USPC **D7/510**

(58) **Field of Classification Search**

(57) **CLAIM**

The ornamental design for a water bottle, as shown and described.

DESCRIPTION

FIG. 1 is a perspective view of a water bottle showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the water bottle that form no part of the claimed design.

1 Claim, 8 Drawing Sheets
